UNITED STATES PATENT OFFICE.

HARLEY E. ANDERSON, OF CHICAGO, ILLINOIS, ASSIGNOR, BY MESNE ASSIGNMENTS,
TO W. H. MINER, INC., A CORPORATION OF DELAWARE.

HAND BRAKE.

Application filed May 14, 1923. Serial No. 638,763.

This invention relates to improvements in hand brakes.

The object of the invention is to provide an exceedingly simple and inexpensive 5 hand brake of the worm and nut type for railway cars, wherein is employed a vertical pull rod.

In the drawing forming a part of this specification, Figure 1 is a view in side elevation of the end portion of a car, showing 10 my improvements applied thereto. Figure 2 is an enlarged, vertical, sectional view of the upper portion of the brake mechanism and the immediately adjacent portion of the 15 end of the car. And Figure 3 is a horizontal, sectional view, corresponding substantially to the line 3—3 of Figure 2, showing the bearing sleeve and pull rod only.

In said drawing, 10 denotes the end wall 20 of a box car, 11, a roof board, 12 a running board and 13 a platform for the brakeman.

The improved brake mechanism comprises, broadly, a pull rod A; a hand wheel 25 B; an upper bearing bracket C; a lower bearing bracket D; a chain guide pulley E; and a pulley bracket F.

The pull rod A is in the form of an elongated cylindrical bar, threaded at its upper 30 end as indicated at 14. The rod A is guided for vertical sliding movement in the brackets C and D and platform 13, and has its lower end connected to one end of a brake chain 15 by means of a pin 16, the opposite end of the 35 chain 15 being connected with the brake mechanism proper. The brake chain 15 is guided in its movements by the grooved pulley E, rotatably journaled in the bracket F, which is rigidly secured to the lower flange 40 of the end sill 17.

The guide bracket D is rigidly secured to the upper flange of the end sill 17, and loosely receives the rod A, the latter being retained within the guide bracket D by a 45 pin 18.

The bracket C comprises an upper substantially cylindrical sleeve portion 19, a lower vertically extending wall portion 20, and a pair of opposite side walls 21 merging at their upper ends with the wall of the 50 sleeve 19 and having their outer edges downwardly inclined and merging with the lower end of the wall 20. At the lower extremity, the wall 20 is provided with a horizontally 55 extending, outwardly projecting lug 22, re-

cessed at its outer end as indicated at 23 to provide a guide bearing for the rod A. The bracket C is also provided with a lug 24, rearwardly projecting from the central portion thereof and inclined transversely to 60 correspond with the inclination of the car roof. The bracket C is rigidly secured in position on the car by lug screws and bolts, or any other suitable means passing through the flange 24 and the wall 20, respectively. 65

The sleeve portion 19 of the bracket C is provided with a smooth bore 25 adapted to slidably receive the threaded end 14 of the rod A for vertical sliding movement. The wall of the bore 25 is provided with a vertically extending rib 26 adapted to co-act with a vertically extending slot 126 in the threaded upper portion of the rod A, to prevent rotation of the rod relatively to the sleeve without interfering with the vertical 75 sliding movement thereof.

The hand wheel B has the hub portion 27 thereof provided with internal threads 28 adapted to co-act with the threaded portion 14 of the pull rod A. The lower face of 80 the hub 27 bears on the upper end of the sleeve 19, and the hand wheel B is thereby freely rotatably mounted on said sleeve.

A collar 29 clamped between the nut 30 and an annular shoulder 31 at the upper end 85 of the rod A, co-acts with the upper face of the hub 27 to prevent the wheel and rod from becoming disassembled when the rod is fed downwardly.

The operation of the device is as follows: 90 To tighten the brakes, the end wheel B is turned in a clockwise direction; the pull rod which is held against rotation by the key rib 19 will be moved upwardly through the medium of the inter-engaging threads of the 95 latter and hub, thereby pulling on the chain 15 connected to the brake mechanism proper. During this operation the downward pull on the hub portion of the hand wheel will keep the same in bearing contact 100 with the upper face of the sleeve 19 of the bracket C. As the operation of tightening the brakes proceeds, the upper end of the rod will be projected above the hand wheel. It will be apparent that this gives visual 105 evidence to a brakeman, even though on the roof of a distant car, whether the brake is set or not.

To release the brakes, the hand wheel is rotated in the opposite direction to that just 110

described, thereby gradually feeding the rod A downwardly until the brakes are fully released, the downward movement of the rod being limited by the collar 29 coming into contact and being stopped by the upper face of the hub of the hand wheel B.

It will be evident that no separate locking means for preventing the release of the brakes is necessary, as the inter-engaging threads on the hand wheel and the pull rod, due to the friction therebetween, act as a holding means to prevent release of the brakes. It will also be evident that, by providing a vertical pull rod which is subject to tension only, instead of the usual rotary staff, which in addition to being subjected to tension is also subjected to torsional strains, a proportionately much lighter rod may be used with consequent economy in first cost.

I have herein shown and described what I now consider the preferred manner of carrying out the invention, but the same is merely illustrative and I contemplate all changes and modifications that come within the scope of the claims appended hereto.

I claim:

1. In a hand brake, the combination with a vertically extending pull-rod having a threaded portion confined to one end, and having the remaining portion smooth and unthreaded, said latter portion being slidably secured to the car wall at spaced points; of a guide bracket associated with the threaded end of said pull-rod, said

bracket being in the form of a cylindrical sleeve portion of less extent than the threaded portion of said rod and having means by which the cylindrical portion is secured in stationary position on the car structure; a hand wheel rotatably supported by said bracket and provided with an internally threaded hub portion adapted to receive and co-act with the threaded portion of said rod; and means for preventing rotation of said rod at all times, said means comprising a vertically extending elongated key integral with the interior wall of said cylindrical portion, said threaded portion of the rod being provided with a vertically extending groove therealong to slidably receive said elongated key.

2. In a hand brake, the combination with a vertically extending pull rod having a threaded portion; of an elongated guide bracket for vertically guiding said rod, said bracket being provided with a cut out portion and an offset portion, permitting the application of means for fastening the bracket to the car structure, and a guide adjacent the end of the cut out portion adapted for engagement with the rod; and a hand wheel rotatably supported by said bracket and provided with an internally threaded hub portion adapted to receive and co-act with the threaded portion of said rod.

In witness that I claim the foregoing I have hereunto subscribed my name this 7th day of May, 1928.

HARLEY E. ANDERSON.
